FILAMENT TREATING

Viktor Beplate, Sydowsaue near Stettin, Germany, assignor to American Glanzstoff Corporation, New York, N. Y., a Corporation of Delaware

Application July 8, 1931, Serial No. 549,554,
and in Germany July 9, 1930

6 Claims. (Cl. 18—8)

1 My present invention has to do with a new method for treating artificial filaments, more especially those produced by the pot spinning method.

5 One object of my present invention is to produce a machine which will act to automatically treat cakes of filaments so that their wet-treatment is facilitated.

10 Another object is to present a machine which will automatically change cakes of filaments to skeins of the same.

Other objects will become apparent from a reading of the following specification and a study of the accompanying drawings, in which:

15 Figure I is a side elevational view of my improved apparatus.

Figure II is an end elevation of the same.

Figures III, IV, V and VI are detailed views of the actuating elements later to be described.

20 In the production of articial filaments by the pot-spinning method, a cellulosic solution (cellulose xanthate; cuprammonium cellulose, etc.) is made up, and after proper preliminary treatment is extruded or expressed through minute openings into a setting or coagulating medium. The 25 filaments are then led over proper guides into a centrifugally spinning container or pot, where they are collected in the form of a cake of twisted filaments. The cake is then after-treated or wet-30 treated so as to wash, bleach, etc. the filaments 35 therein. My present invention has to do with such cakes, and a new method for treating the same.

When filaments are produced by the viscose or 40 cellulose xanthate method, it is necessary to de-acidify, desulphurize, wash, bleach and perhaps size the filaments in the wet-treatment thereof. This wet-treatment may be accomplished by arranging skeins of the filaments in rows under a 45 dripping apparatus, and allowing the treating liquids to drip thereover until the necessary results are accomplished. My new device automatically moves cakes of filaments to the drip-treating arrangement and while so moving them 50 changes them to the form of skeins by pressing them together at the sides.

55 My device consists essentially of a fixed frame (1) supporting transporting rails (3) and (4). The cakes of filaments (C) are arranged on sticks (2) and arranged in rows upon the transporting means (3) and (4). The movement of the sticks (2) and the cakes (C) is accomplished by the reciprocal motion of the movable rails (3) and the fixed rails (4). Arranged within the fixed frames (1) there is a movable frame

(5) to which the rail (3) is attached. This movable frame (5) is actuated by the crank-like arrangement (6). Through motion of the cranks (6), the carrier frame (5) is put in motion so that it describes a circular motion lying in the longitudinal plane of the entire machine. Notches (n) (Figures III through VI) are provided so that they are situated at such a position that the sticks (2) are engaged after each cycle of rotation of the movable rod (3). By the use 60 of these notches, the movable rail portion describes a circle, actuated by means of the crank (6) through the movable frame (5) and lifts the sticks. As the circle is nearly completed, the sticks or rails (2) are loosened and lie in the 65 notches (n) until grasped by the next succeeding portion (3) in its circular movement. This moves the sticks or rails progressively along the frame. The sticks, thus progressing, carry the cakes through the gripping means for compressing 70 them into a skein-like form, and to the end portion of the machine where they may be treated by the drip treatment method described above.

75 The actual gripping arrangement provided for the formation of the skein-like groups of filaments is set forth in Figures III through VI. In Figure I, I have shown how the frame portion (1) is provided with a holding arrangement or rod (7) where at the fixed point (8) the plates (9) and (10) are attached. These latter are 80 shown in detail in the last four figures of the drawings. These plates (9) and (10) are moved, 85 respectively by the actuating rods (12) and (11), which are pivotally connected to the movable frame (3). As can be seen from a study of the 90 drawings, this combination of frames with common joints and a fixed frame, on the one hand, and the rods (11) and (12) with the movable frame (3) on the other hand act so that the pairs of plates (9) and (10) are opened and 95 closed, or moved to and from one another, by the rotating movement of the movable carrier frame. Through the opening and closing of these frames (9) and (10), the spinning cakes as they pass are gripped and compressed to a certain extent, thus producing a skein-like formation (S). The pressing plates (9) and (10) may consist 100 of oblong wide boards which extend over the entire length of a whole row of spinning cakes, or, as an alternative, the pairs of plates which 105 operate together may be connected to the pairs of plates located on each side of the arrangement and situated so as to press the cakes on one of the rods at a single time.

110 In the disclosed arrangement I have provided a

means whereby the sticks or rods carrying the cakes progress for a greater distance when the filaments are in the form of cakes, and during their transformation into skeins than afterwards when they are in skein form. In order to accomplish this, the levers (13) and (14) have been provided, which levers move upon the bolts (15) and (16) of the movable rail (3). The levers (13) and (14) are provided with slots (17) and (18) in which the steering bolts (19) and (20) are run. These two bolts (19) and (20) are themselves connected to the fixed rail portion (4). Upon the reciprocal motion of the rails (3) and (4) the levers (13) attached to both sides of the machine seize with their upper jaws or portions the washing sticks (2) with the cakes (C), lift them up (Figure IV), carry them just below the pressing plates (Figure V), where they are pressed together in the manner indicated above (Figure VI.) During the same operation, and in a similar manner, the levers (14) seize the just folded cakes lying under the pressing plates (Figure III), lift them, (Figure IV), and carry them to the grooves placed at the right of the arrangement (Figures V and VI). The operation for the pressing by the plates (9) and (10) takes place correspondingly and simultaneously with the advancing of the sticks and cakes by the levers. As indicated in Figure III, the plates (9) and (10) open to clear the way, and according to Figure IV the already folded cake may be advanced and the next cake to be pressed brought under the plates. Figure V shows the plates just as they are advancing towards the cake to press it into the form shown in Figure VI.

I have shown several grooves placed before the portion of the arrangement where the gripping plates (9) and (10) operate, but these are provided for the purpose of having a reserve of the sticks and cakes on hand to facilitate the continuous operation of the machine.

After being thus handled, the sticks containing the yarn may be transported to some other location for the wet-treatment process, or, as indicated by Figure II (right-hand portion) a wet-treatment device may be combined with the machine itself.

In certain cases it may be found convenient or necessary to moisten the spinning cakes before they are pressed together, and for this purpose I have provided dripping grooves (22).

In some instances it is found advisable to so arrange the gripping plates (9) and (10) that they do not press the cakes together too far. If they are pressed too close together, they tend to grip the carrying stick (2) and so impede the working thereof. In order to adjust the plates, the push bars (11) and (12) may be arranged in a suitable position, or the bolts between the pressing plates (9) and (10) may be adjusted. One means for providing for such an adjustment is indicated by the slots (a) and (b) in (11) and (12).

The various machine parts which come into

contact with the treating liquid may be made of some suitable matter which is resistant thereto. The pressing plates may be made of hard rubber or bakelite, or may be covered by the material of which the rest of the frames is composed.

Having now set forth my invention as required by the patent statutes, what I wish to claim is:

1. A device for automatically folding or pressing together cakes of filaments comprising movable frames and a gripping mechanism, said gripping arrangement being actuated by the movement of one of the movable frames.

2. In a device for treating filaments, an outer frame, an inner frame actuated by a crank-like device, a series of fixed frames and a series of movable frames, a gripping device the first mentioned movable frame when actuated by the crank describing a circular motion which progressively feeds sticks containing the filaments to the gripping device, which gripping device is actuated by the movement of the last mentioned movable frames.

3. A device for the treatment of filaments comprising sticks holding cakes of the filaments, means for moving the sticks progressively towards a gripping device, and means for gripping the cakes to press them into the form of skeins.

4. The device as set forth in claim 3 in which the sticks are continuously moved after the gripping thereof.

5. In a device for treating filaments, an outer frame, an inner frame actuated by a crank-like device, a series of fixed frames and a series of movable frames, a gripping device attached to said outer frame, and actuated by said movable frame, when said movable frame describes a circular motion which progressively feeds sticks carrying the filaments to said gripping device, said gripping device consisting of opposed plates having at each end arms attached thereto, said arms being pivoted at their upper end to said outer frames, said arms being link-connected to said movable frames and actuated thereby for the purpose of gripping the cakes to press them into the form of skeins.

6. In a device for treating filaments, an outer frame, an inner frame actuated by a crank-like device, a series of fixed frames and a series of movable frames, a gripping device attached to said outer frame, and actuated by said movable frame, so that said movable frame may describe a circular motion and progressively feed sticks containing the filaments to said gripping device, said gripping device consisting of opposed plates having at each end arms attached thereto, said arms being pivoted at their upper end to said outer frames, said arms being link-connected to said movable frames and actuated thereby for the purpose of gripping the cakes to press them into the form of skeins, said link connections acting as push bars and having means for adjusting the movement of said gripping mechanism.

VIKTOR BEPLATE.
